ADJUSTING MEANS FOR HYDRAULIC GOVERNOR COMPENSATING SPRINGS

Robert W. Taylor, United States Navy

Application October 4, 1945, Serial No. 620,378

2 Claims. (Cl. 267—1)

(Granted under the act of March 3, 1883, as amended April 30, 1928; 370 O. G. 757)

1

This invention relates to speed governors equipped with hydraulic compensating or stabilizing mechanism and more particularly to improved adjusting means for modifying the action of the compensating mechanism to provide close regulation and prevent hunting of the prime mover.

It is known in the art to provide governors with hydraulic compensating or stabilizing mechanism which will operate to eliminate or reduce within practical limits hunting of the governed prime mover during load changes. However, means have heretofore been unknown for making fine adjustments of the compensating mechanism embodied in commercial designs without disassembling the mechanism. This is objectionable in view of the time and skill which is necessitated in making accurate adjustments for close regulation of the prime mover.

An object of the invention is to provide in a governor of the above described character a novel adjusting mechanism which may be pre-set more accurately than speed compensation controls heretofore provided.

Another object is to provide an improved adjusting mechanism for governor hydraulic compensating means which may be operated externally of the governor casing without disassembling the governor mechanism or component parts thereof.

A further object is to provide an improved adjusting mechanism for controlling the hydraulic compensating means of a governor which may be securely locked in the adjusted position.

The invention also resides in certain novel structural characteristics which facilitate carrying out the foregoing objects and which contribute both to the simplicity of the adjustable governor hydraulic compensating mechanism and to the reliability of operation as well as to the ease and expeditious manner of making the desired adjustments.

Other objects and advantages of the invention will become apparent from the following detailed description taken in connection with the accompanying drawings, in which:

Figure 1 is a vertical sectional view through a governor made in accordance with one embodiment of the invention;

Figure 2 is a horizontal section on line 2—2 of Figure 1;

Figure 3 is an enlarged detailed view taken on line 3—3 of Figure 2 showing the embodiment of the valve compensation spring and adjusting means disclosed in Figures 1 and 2;

2

Figure 4 is a longitudinal sectional drawing through a governor having modified arrangements of parts, and

Figure 5 is an enlarged detailed view showing the valve compensating spring and adjusting means embodied in the governor mechanism shown in Figure 4.

While the invention is susceptible of various modifications and alternative constructions, I have shown in the drawings and will herein describe in detail the preferred embodiments. It is to be understood, however, that I do not intend to limit the invention by such disclosure for I aim to cover all modifications and alternative constructions falling within the spirit and scope of the invention as defined in the appended claims.

The drawings show the invention incorporated in a main hydraulic governor 10 which operates alternately in response to small increases and decreases in the speed of a prime mover (not shown) to adjust the position of a rod 11 connected through a mechanical linkage 12 to a fuel pump, gas mixing valve, throttle valve or other device indicated by reference numeral 13 for controlling the supply of an energy medium to maintain the speed of the prime mover substantially constant.

Referring to Figure 1, the governor 10 is formed of a governor body 14 positioned upon a base 15 which may be secured on or adjacent to the prime mover. A spring biased hydraulically actuated servomotor 16 which serves to modulate the speed of the prime mover is supported adjacent to one side of the governor body 14. The servomotor comprises a hollow element 17 in which is formed a main cylinder 18 between member 26 and spring cover 23 and an auxiliary cylinder chamber 19 between member 26 and apertured closure plate 24. Secured by nut 25 to one end of rod 11 is a main piston 20 located in cylinder chamber 18. An auxiliary piston 21 is secured intermediate the ends of rod 11 in cylinder chamber 19. One end of cylinder chamber 18 is closed by the spring cover 23 and one end of cylinder chamber 19 is closed by the aperture closure plate 24 which contains suitable bearing through which rod 11 passes. Openings 27 and 28 are provided in hollow element 17 for the passage of fluid to and from cylinder chambers 18 and 19, respectively. A compression spring 22 serves to urge the main piston 20 together with the auxiliary piston 21 and rod 11 in a downward direction. Downward movement of rod 11 transmitted through linkage 12 actuates the fuel controlling

device 13 to reduce the energy medium flowing to the prime mover.

As shown in Figures 1 and 2, the governor body 14 is provided with a centrally positioned longitudinal bore 30 in which the speed responsive valve mechanism is located. This mechanism comprises an elongated rotatable sleeve 31 fitted for rotation within longitudinal bore 30. Rotatable sleeve 31 has a central opening extending longitudinally thereof and the lower portion is enlarged to form a cylinder chamber in which is enclosed a piston 47 and a compensating spring assembly. A plurality of apertures 37, 38, 39 and 40 extend radially at spaced intervals throughout the length of said rotatable sleeve. Pilot valve bushing 32 is contained within the central opening of the rotatable sleeve 31 and consists of a tubular upper portion 33 and a piston 47 secured to the lower extremity of the tubular portion. Ports 41 and 43 and regulating port 42 are formed at spaced intervals in the tubular portion 33 of valve bushing 32. Extending from said tubular portion 33 is a rod 34 having its end threaded to receive an adjusting nut 35. An additional element of the valve mechanism comprises a pilot valve plunger 36 adapted for sliding movement within the tubular portion 33 of pilot valve bushing 32. A plurality of lands 44, 45, and 46 are located at spaced distances between the ends of the pilot valve plunger as shown in Figure 1.

Hydraulic pressure for the operation of the governor parts is supplied by a pump formed of driving spur gear 50 positioned at the lower extremity of longitudinal bore 30 and journaled at 52 in base 15 and a driven spur gear 51 which is mounted on stub shaft 53 in recess 54 formed in body 14. The driving spur gear 50 is hollowed to receive the splined section of drive shaft 55 which extends through base 15 and is fitted with suitable drive members such as bevel gears 56, 57 and shaft 58 which serve to connect shaft 55 for rotation to the prime mover. Base 15 is provided with a suitable bearing and oil retainer which support and maintain the drive shaft 55 in the position shown in Figure 1. An extension 59 of the driving spur gear 50 is connected by screws 60 to rotatable sleeve 31 so that the sleeve and driving spur gear are rotated as a unit by the prime mover.

The upper extremity of the rotatable sleeve 31 is connected to a yoke 61 provided with pivots 62 which serve to support bell cranks 63. One arm of each of the bell cranks 63 is threaded to receive correspondingly threaded nuts 64 which serve as the fly balls for the governor. The other arm of each bell crank engages the outer race of ball bearing 65. It will be apparent that rotation of rotatable sleeve 31 will serve to rotate yoke 61 and that fly balls 64 which are free for radial movement by centrifugal force will assume various positions depending upon the speed of the prime mover. Radial movement of the fly balls will cause the bell cranks 63 to rotate about pivots 62 and move bearing 65 either upward or downward in a vertical direction. Outward movement of the fly balls 64 is resisted by speeder spring 66 which has one end seated on a collar 67 and the other end engaging an adjustable abutment 68. The position of the abutment 68 may be manually adjusted by means outside of the governor casing (not shown) by rotation of pinion 69 which engages the rack 70 to move the abutment in its slidably mounted identified by reference numeral 71. Collar 67 is secured to an extension 72 of pilot valve plunger 36 which

extension is tightly fitted to the inner race of ball bearing 65. Thus the pilot valve plunger may be moved in a vertical direction by the action of the fly balls, but it will not rotate with the yoke 61. A cover 13 secured to governor body 14 is provided to enclose the fly balls, speeder spring, and mountings as is shown in Figure 1.

One modification of the compensating spring and adjusting means therefore is best shown in Figures 2 and 3. An upper spring collar 76 is slidably mounted on rod 34 and maintained a spaced distance from piston 47 by spacer 75. A sleeve 77 is secured to the interior of the rotatable sleeve 31 by screw 78 and a portion 79 thereof extends between collar 76 and piston 47. The lower spring collar 80 is cupshaped and the bottom is centrally drilled and tapped to receive the correspondingly threaded shank of flange 81. Compensating spring 85 is positioned between upper spring collar 76 and lower spring collar 80. Flange 81 is provided with a central opening to slidably receive rod 34 and nut 35 prevents rod 34 from slipping through the flange when pilot valve bushing 32 is raised. As is shown in Figure 3, flange 81 bottoms on ledge 82. The flange is connected to sleeve 77 by pin 83 which projects into a vertical slot 84 formed in sleeve 77. As shown in Figure 2, the lower spring collar 80 is exteriorly threaded to receive the threads of a worm 90 which is mounted in chamber 91. Chamber 91 extends tangentially into the sleeve 77 and rotatable sleeve 31. Worm 90 is provided with a shank 92 which is fitted for rotation in extension 93 of chamber 91. On the end of the worm opposite the shank 92, a socket 94 is provided which constitutes a female coupling element for the worm. A set screw 95 having a central bore is positioned in an enlarged threaded extension of chamber 91 and is adapted to be tightened against worm 90 to secure it in an adjusted position. In addition to the central bore, set screw 95 is provided with castellations 96 which serve as a female coupling connection. It will be noted from Figure 2 that the threads of worm 90 are in engagement with the exterior threads of the lower spring collar 80 and that the assembly of set screw 95, worm 90, lower spring collar 80, sleeve 77 and rotatable sleeve 31 are rotated in unison by the prime mover.

Manual means for adjusting the vertical position of lower spring collar 80 and hence the compression of compensating spring 85 and also for securing the adjustment of the collar from outside of the casing are indicated by reference numeral 100 in Figure 2. Governor body 14 is bored at 101 and 102 and drilled and tapped at 103 to engage the external threads of bushing 104 which extends through the outer wall of the governor body. Positioned within the bushing and extending from the exterior into the interior of the governor body 14 are worm operating shaft 105 and set screw operating shaft 106 which are concentrically located and arranged for sliding movement. Set screw operating screw shaft 106 comprises a tubular member provided at the outer end with a handle 113 and at the inner end with a male coupling means 108 adapted to engage the castellated coupling of set screw 95. Shaft 106 is slidably mounted in bushing 104 and is urged out of contact with set screw 95 by compression spring 109. Coaction of an enlarged portion or land 112 on shaft 106 with an offset portion of the bushing serves to limit the outward movement of the shaft. A pressure seal

between bushing 104 and slidable shaft 106 is provided by a gland 110 which maintains packing material 111 in place between shaft 106 and bushing 104. Worm operating shaft 105 which is slidably mounted within shaft 106 is provided at its outer end with handle 107 and at its inner extremity with male coupling element 114 which is adapted to engage with socket 94 of worm 90. Compression spring 115 serves to urge shaft 105 out of engagement with worm 90 and the engagement of collar 116 with handle 113 limits the outward movement of the shaft. Cover 117 which is internally threaded at its open end to engage externally located threads on bushing 104 is positioned over handles 107 and 113 to prevent accidental sliding of the corresponding shaft inwardly during operation of the governor.

The mechanism above described enables the position of the lower spring collar 80 to be varied in a vertical direction from without the governor casing which in turn will serve to pre-set the tension of compensating spring 85. When it is desired to make an adjustment, rotatable sleeve 31 is positioned with chamber 91 in axial alignment with coupling elements 114 and 108 on shafts 105 and 106 respectively. This can readily be done by removing inspection plate 118 and aligning the yoke 61 with an appropriate mark on the governor body. Cover 117 is removed to expose the operating handles 113 and 107 and shaft 106 is pushed inwardly against the action of spring 109 until the male coupling means 108 engages the female coupling means of set screw 95. The set screw 95 and shaft 106 are rotated by handle 113 in a direction to back-off the set screw thus unlocking worm 90. Shaft 105 is then moved inwardly until the male coupling means 114 engages socket 94 of worm 90. With the parts in this position, the worm may be turned by handle 107 which in turn causes the lower spring collar 80 to rotate on the threads of flange 81. In this manner the spring collar may be raised or lowered to pre-set the tension of spring 85. After the desired adjustment has been made, coupling means 114 and 94 are disengaged and shaft 105 returned to the position shown in Figure 2 by the action of spring 115. Shaft 106 is pressed inwardly so that coupling means 108 and 96 are in engagement and the set screw 95 is rotated by handle 113 to lock worm 90 in its adjusted position after which handle 113 is released and spring 109 serves to return it to the position shown in Figure 2.

The intake to spur gear pump 50-51 communicates with a sump identified by reference numeral 120 in which oil or other hydraulic fluid is contained. The hydraulic fluid is inserted through filler opening 99 and flows to the sump through passages (not shown). The discharge side of the pump communicates with the storage chamber of accumulators 121 provided with pistons 122 which are biased by springs 119 whereby a relatively constant oil pressure is maintained. A by-pass (not shown) is employed in a known manner from the discharge side of gear pump 50-51 to the sump for relieving excess oil pressure.

When the prime mover is rotated at normal speed under steady load, the flyballs 64, pilot valve plunger 36 and pilot valve bushing 32 are in normal positions with respect to the regulating port 42 in the pilot valve plunger as shown in Figure 1.

Upon decrease of load upon the prime mover, its speed increases and the flyballs 64 are moved

outwardly by centrifugal force. Outward movement of the flyballs causes the pilot valve plunger 36 to be raised whereby land 45 uncovers regulating port 42 in the pilot valve bushing 32. This completes an open oil passage from main cylinder chamber 18 to the sump through opening 27, duct 123, aperture 38, regulating port 42, and port 43 and the compression spring 22 serves to move the main piston 20 downwardly which results in the downward movement of rod 11 which actuates the fuel supply control 13 through linkages 12 to decrease the fuel supply to the prime mover. As the main piston 20 and rod 11 move downwardly, auxiliary piston 21 also moves downwardly, drawing oil into auxiliary piston chamber 19 from above pivot valve bushing piston 47 through opening 28, duct 124 and aperture 40 resulting in the upward movement of pilot valve bushing 32 and the expansion of spring 85. This movement continues until the regulating port 42 is covered by land 45 at which point the main piston 20 and rod 11 are stopped in a position corresponding to the decreased amount of fuel necessary to operate the prime mover at normal speed under the decreased load. As the speed decreases to normal, flyballs 64 move radially inward to normal position due to the decreased centrifugal force, causing the pilot valve plunger 36 to be lowered to normal position. The compensating spring 85 acts to return the pilot valve bushing 32 to normal position at the rate the pilot valve plunger moves thus keeping the regulating port 42 covered by land 45 and the main piston 20 stationary. The rate of movement is controlled by the pre-set compression of spring 85 and rate of oil flow through needle valves 125. At the completion of the cycle above described, the flyballs 64, pilot valve plunger 36 and pilot valve bushing 32 are in normal positions and the main piston 20 is stationary at a position corresponding to the decreased amount of fuel needed to operate the prime mover at normal speed under the decreased load.

Upon increase of load on the prime mover, its speed decreases and flyballs 64 move radially inward by lowering pilot valve plunger 36 which causes regulating port 42 to be uncovered by land 45. This completes an open passage between the oil under pressure in the accumulator 121 to main cylinder chamber 18 thru aperture 37, port 41, regulating port 42, aperture 38, duct 123 and opening 27 resulting in the upward movement of main piston 20 and rod 11 against the pressure of spring 22 and actuation of the fuel supply control 13 through linkages 12 to increase the fuel supply to the prime mover. Upward movement of rod 11 causes upward movement of auxiliary piston 21 which serves to force oil from auxiliary piston chamber 19 into piston chamber 48 through opening 28, duct 124 and aperture 40 resulting in the downward movement of pilot valve bushing piston 47 and the compression of spring 85. The downward movement of pilot valve bushing piston 47 continues until the regulating port 42 is covered by land 45 on the pilot valve plunger 36 at which time the main piston 20 is stopped at a position corresponding to the increased fuel needed to operate the prime mover at normal speed under increased load. As the speed increases to normal, flyballs 64 return to normal position raising the pilot valve plunger 36 to normal position. The pilot valve bushing 32 is returned to normal position by the action of the compensating spring 85 at the same rate as the pilot valve plunger 36 thus keeping the regu-

lating port 42 covered by land 45 and the main piston 20 stationary. The speed of return of the pilot valve bushing is dependent upon the adjustment of the needle valves 125 and the adjustment of the compensating spring. At the completion of the cycle above described the flyballs 64, pilot valve plunger 36 and pilot valve bushing 32 are in normal positions and the main piston 20 is stationary at a position corresponding to increased fuel needed to operate the prime mover at normal speed under increased load.

The alternative governor construction disclosed in Figures 4 and 5 operates on the general principles set forth above although the parts have been rearranged and redesigned so that the preset compression of compensating spring 130 may be manually adjusted from outside of the governor body 131 while the prime mover and the governor are in operation. In this modification, yoke 132, pivoted bell cranks 133 and flyballs 134 are adapted to be rotated in bearing 167 by shaft 135 which is connected to the prime mover (not shown). Shaft 135 is connected to driving spur gear 136 which meshes with driven spur gear 137, both constituting a pump for supplying oil pressure to the governor. Gear 140 attached to yoke 132 is driven by the driven spur gear 137 through shaft 138 and gear 139. The inner extremities 141 of bell crank arms 133 are pivotally connected to extension 142 of pilot valve bushing 143 which is connected to the inner race of ball bearing 144. Speeder spring 145 is mounted between the outer race of ball bearing 144 and the manually adjustable abutment 146. As will be noted in Figure 4, the speeder spring tends to bias the flyballs 134 inwardly. Pilot valve bushing 143 is provided with port 148 and regulating port 149 which cooperate with chambers in the governor body 131, and is recessed at the bottom to receive the pilot valve plunger 150. In this modification, pilot valve plunger 150 is provided with land 151 and also land 152 which normally covers regulating port 149. The plunger is attached at 153 to the lower extremity of pivot valve plunger piston 154 located in compensating spring chamber 155. The top of compensating spring 130 presses against the bottom side of piston 154 and the spring bottoms on adjustable spring collar 156 which is cut-shaped and provided with threads 157 on the periphery thereof. The bottom is drilled and tapped at 158 to receive the threaded shank 159 of flange 160 which is secured against rotation in the lower part of cylinder chamber 155. The threads 157 on the outer periphery of spring collar 156 are engaged by worm gear 161 which is manually rotated by shaft 162. Shaft 162 extends outside of the governor body and is provided with an operating handle (not shown). Rotation of worm gear 161 serves to rotate spring collar 156 on the threaded shank 159 which results in movement of the collar in a vertical direction in order that the compression of compensating spring 130 may be adjusted.

The servo-motor identified by reference numeral 165 comprises a casing 166 secured adjacent to governor body 131. The casing is recessed and partitioned at 170 to provide cylinder chambers 167 and 168. Piston 169 is located within the recess and has operating faces 171 and 172 located in cylinder chamber 167 and 168, respectively. The piston 169 is secured to shaft 173 which is connected at its upper end to compression spring 174 and at its lower end through mechanical linkage to the mixing valve, fuel pump, throttle valve or other device (not shown)

for controlling the supply of an energy medium to the prime mover. A duct 175 extends between cylinder chamber 167 and regulating port 149 and duct 176 extends between cylinder chamber 168 and cylinder chamber 155 in which the pilot valve plunger piston is located. A needle valve represented by reference numeral 177 is provided in order to relieve the oil pressure existing therein to sump 178. The operation of the modified governor to maintain constant speed of the prime mover upon either increase or decrease of load is substantially the same as the operation above set forth except that in this modification, the radial movement of the flyballs 134 serves to move the pilot valve bushing 143 and the compensating action of spring 130 is applied through pilot valve plunger 150.

From the above description it will be apparent that the compensating spring of the governor can be accurately pre-set to prevent hunting and to obtain close regulation of the prime mover without disassembling of the governor. The adjustment of the compensating spring can conveniently be made by manipulation of the externally positioned controls and after the adjustment is made, the mechanism can be secured in the adjusted position in order to maintain the regulating action of the governor.

The invention described herein may be made or used by or for the Government of the United States for governmental purposes without the payment to me of any royalties thereon or therefor.

I claim:

1. In a hydraulic speed responsive governor of a type having a liquid valve means for controlling the speed of a prime mover, an adjustable compensating spring for eliminating surging and hunting of the prime mover and adapted to bear at its upper end against a movable member, means for manually adjusting the precompression of said compensating spring, said manually adjusting means comprising a cup shaped collar for supporting the lower end of said spring, a worm gear mounted on the outer side of said collar, a worm mounted adjacent said collar and adapted to engage said worm gear, said worm, worm gear and collar being constructed and arranged to effect the adjustment of said spring upon the rotation of said gear and collar by said worm, means for locking said spring in its adjusted position, said adjusting and locking means further comprising a tubular shaft extending transversely of said collar and in axial alignment with said worm, a second shaft concentrically mounted within said tubular shaft, said tubular shaft having means on one end thereof adjacent said collar for unlocking said collar, said second shaft having means on one end thereof adjacent said collar for adjusting said collar, means normally maintaining said shafts out of engagement with said collar, handle means positioned on the opposite ends of said shafts to facilitate turning of said shafts to the desired position, and means for enclosing said shaft handles when said handles are not in use.

2. In a hydraulic speed responsive governor which includes a speed-control means including a movable support, an adjustable compensating spring adapted to bear at its upper end against said movable support, means for manually adjusting the precompression of said spring, said manually adjusting means comprising a cup shaped collar for supporting the lower end of said spring, indentations imposed on the outer side
